TWISTERS

Ernest Graf, Biddeford, Maine, assignor to Saco-Lowell Shops, Boston, Mass., a corporation of Maine

Application August 31, 1953, Serial No. 377,402

8 Claims. (Cl. 57—58.84)

This invention relates to textile twisting machines of the so-called "2 for 1" type, and more particularly to a novel yarn storage wheel structure for use on such machines.

As is well understood by those skilled in the art, a machine of this type is so organized as to put two turns of twist into the yarn, thread, or other strand to be twisted for each revolution of the spindle. A prior art machine of this type comprises a revolving vertical spindle on which is mounted a stationary spool from which the yarn is drawn, the spool being supported by a normally stationary carrier rotatably mounted on the spindle. Commonly, magnets are used to maintain the carrier in stationary position. The spindle and the spool support, or carrier, have a central passage therethrough for guiding the yarn unwound from the spool to a yarn passage and an opening in a yarn storage wheel which supplies a tension to the yarn. The yarn is drawn from the supply package down through the central passage and through a radial opening in the yarn storage wheel. From there it describes a balloon surrounding the supply package in its upward travel through a balloon gathering eye to a suitable take-up or winding mechanism. Thus, for each revolution of the spindle, one turn of twist is imparted to the yarn as it leaves the supply package during its travel to the storage wheel, and another turn as it balloons upward from the storage wheel to the take-up mechanism.

In such machines the means for adjustment and the ensuring of uniformity of tension are extremely important. The yarn tension is controlled at two stages; first, during the downward passage to the storage wheel and second, during the upward passage. The tension applied during the first stage can also be called a pre-tension and may be produced by a number of known means; a preferred means being shown in the U. S. patent application of Marsh, Serial No. 300,439, filed July 23, 1952, now Patent No. 2,731,787. The final tension on the balloon is automatically regulated by the storage wheel essentially as shown, for example, in U. S. Patent No. 1,900,037. A reserve of "wrap" or yarn coils around the periphery of the storage wheel before forming the actual balloon. This wrap is due to the air resistance which the ballooning yarn encounters and which, being greater than the centrifugal force of the yarn balloon, causes the yarn balloon to be deflected backwards and automatically to wrap itself around the storage wheel. The wrap around the storage wheel causes an additional friction on the yarn which will increase to a point at which an equilibrium with the balloon forces is reached. This equilibrium is disturbed if the pre-tension on the yarn changes, as is the case if the yarn drawn from the supply package encounters more tension; for example, as the supply package size diminishes. In this case, the amount of wrap on the storage wheel decreases and with it automatically the amount of yarn tension prior to ballooning, thereby keeping the balloon tension constant.

In order to be able to maintain a constant balloon tension, it has been found to be imperative that in all

2

cases some amount of wrap be present on the storage wheel periphery at all times. There are, however, a number of factors which will affect the amount of wrap. For instance, the air resistance to the ballooning yarn varies with the spindle speed and with the size of the yarn to be twisted. Also these yarns encounter different tensions as they are drawn from various types of supply packages. Thus, if one diameter of storage wheel is to be used under a wide variety of conditions, such wheel must be arranged to maintain a minimum amount of wrap with the lightest yarn and the greatest pre-tension, and yet the same wheel will, however, have to be capable of containing several wraps with the heaviest yarn and the lightest pre-tension.

Storing multiple turns of yarn on the storage wheel has heretofore, however, presented a problem of overlapping, which resulted in uneven tension and sometimes in yarn breakage with consequent delay and loss of production. Such overlapping will take place, for example, when the spindle is started up, as before rotation, and due to the initial upward pull, as the yarn travels to the take-up mechanism, it leaves the storage wheel at the uppermost edge of the radial opening in the storage wheel periphery. As the spindle starts and picks up speed and the yarn begins to wrap around the storage wheel periphery to establish an equilibrium with the yarn balloon, I have found that the wrap in forming itself takes a downward sloping path from the upper most edge of the opening as far down as the storage wheel flange, which flange prevents the wrap from falling downwardly off the storage wheel. Under these conditions, then, if there is more than one wrap about the storage wheel, the yarn will cross itself and overlap where it slants down from the opening.

Accordingly, it is an object of the present invention to provide a 2 for 1 twister having a yarn storage wheel structure which will guide multiple turns of yarn onto said wheel in non-overlapping relation upon the starting of a spindle and during its operation.

A further problem in the operation of 2 for 1 twisters is the continuous feeding of yarn from the opening in the yarn storage wheel when the yarn breaks, particularly if the break occurs in the balloon. The broken end will then extend horizontally from the storage wheel and, due to centrifugal force, will be hurled outwardly and continue to be taken from the supply package. This frequently fouls adjacent spindles on the frame, causing additional yarn breakage.

It is thus a further object of the present invention to provide a 2 for 1 twister spindle that will prevent continued feeding of the yarn upon yarn breakage.

It is a particular feature of the present invention that its structure is extremely simple both in construction and operation and is adapted for most efficient operation with a wide variety of yarns without changes.

For the purpose of more fully explaining a preferred embodiment of my invention reference is made to the following detailed description together with the accompanying drawings in which:

Fig. 1 is a general elevational view of the 2 for 1 twister embodying my invention;

Fig. 2 is a cross sectional elevational view, partly broken away, of the twister of Fig. 1; and

Fig. 3 is a cross sectional plan view of the twister of Fig. 1, taken on the line 3—3 of Fig. 1.

Referring to the drawings, the 2 for 1 twister includes a vertical spindle rotatably mounted on a twister frame 10 which commonly is arranged to mount a relatively large number of such spindles. The spindle generally includes a non-rotatable blade 12 suitably mounted on said frame 10, such as by nuts 14 and rubber washers 16,

the blade 12 rotatably supporting a spindle whirl 18. The whirl 18 may be driven to rotate portions of the spindle structure by a tape (not shown) in the well known manner. The upper portion of the spindle has an axial yarn passage 19 therethrough as is common in 2 for 1 twisters.

A normally stationary yarn package carrier 20 is rotatably mounted on said spindle as by anti-friction bearings 22, such yarn package carrier being maintained in stationary position by magnetic means as more fully described in Patent No. 2,374,085 to E. C. Gwaltney. Such means may consist of horse shoe magnets mounted in fixed position relative to twister frame 10 by a bracket 24. The yarn package 20 is arranged to hold a spool 26 surrounding said carrier, an annular ring 28 of rubber or other resilient frictional material being provided on the upper surface of the lower flange of said carrier for holding said spool, the spool 26 being shown (Fig. 1) as having yarn S wound thereon in the usual manner. The upper end of normally stationary spool 26 is provided with an upper flier mounted for free rotative movement with respect to the normally stationary spool, said flier including a horizontal disc 30 having a guide member 32 of heart shape extending downwardly from the peripheral edge of said disc outside of the spool 26. At the upper portion of said heart shaped guide at opposite edges thereof are provided yarn guiding slots 34 through which the yarn S is threaded, said guide providing means for unwinding the yarn from the spool at an angle substantially perpendicular to the axis of the spindle, as the yarn S passes from the spool 26 across the face of the heart shaped guide 32 to the slot 34 and finally to the axial passage through the spindle as indicated in Fig. 1. A simple friction disc 36 maintained in non-rotative position but still free to move vertically and in frictional engagement with the upper surface of upper flier disc 30 provides a simple and effective means for braking the rotation of the upper flier which is imparted to said flier by unwinding of yarn S from the spool 26 through engagement of said yarn by said upper flier surfaces to provide a pretension on the yarn. The amount of such pretension may be quickly and easily adjusted by varying the amount of such braking which may be most easily accomplished by changing the weight and/or material of the friction disc 36 to provide the amount of braking most desirable for the particular yarn which is to be unwound.

According to the present invention, a lower flier structure is mounted on the spindle for rotation therewith below the spool 26, said structure including a cup shaped flier 38 having mounted at the bottom thereof a yarn storage wheel having an outer cylindrical surface 40 concentric to said spindle. The outer surface 40 of said wheel extends lengthwise of the spindle for a length sufficient to provide for storage of a plurality of turns of yarns on said surface, although in the drawings, for simplicity, but slightly more than one turn of yarn S is shown wrapped around said surface. Furthermore, such surface need not be continuous to be operative, but may, for example, consist of a plurality of spaced pins defining an interrupted substantially cylindrical surface. A rim or flange 42 is provided at the lower edge of said cylindrical storage surface 40, the upper surface 44 of said flange being slanted outwardly and downwardly from the yarn storage surface 40 to permit broken yarn to pass downwardly over the slanted edge and be wound up and held in an annular groove 46 having a reduced diameter in the spindle whirl 18, such groove being positioned immediately below the yarn storage wheel at the lower end of axial passage 19. Although the degree of slant of the flange surface 44 is not critical, I have found that an angle from the spindle axis of from 20° to 60° is satisfactory, with 30° being preferable, since if the angle is too great the yarn will tend to slip downward from the storage wheel surface even though unbroken.

An outer opening is provided in the storage wheel surface 40, said opening extending through the lower edge

of the wheel flange 42 and being defined at its top by flier 38 and at its sides by slanted yarn guiding edges 48, a yarn guiding passage 50 being provided in the lower surface of said storage wheel leading from the axial yarn passage 19 of the spindle to said outer opening. The passage 50 is open along the lower surface of the yarn storage wheel to facilitate threading yarn through the spindle, as well as to enable broken yarn to fall off the yarn storage wheel, and be wound up in groove 46 as hereinafter explained. A pair of spaced, oppositely slanted yarn guiding edges 48 are provided at each side of the outer opening to permit rotation of the spindle in either direction, but one of said edges operating at a time to provide a yarn guiding edge which preferably extends across the entire face of the storage wheel cylindrical surface 40. Of course, if the spindle is to be operated in but one direction, only one slanted guiding edge need be provided.

The working yarn guiding edge 48 is slanted with its upper end leading its lower end in the direction of rotation of the spindle, so that, when the spindle is revolved, said working edge is effective to provide a downward component of force upon yarn passing from the storage wheel opening tangentially of the storage wheel to guide the yarn in a downward direction. The angle of slant of edges 48 is preferably at least 5° and may be much greater to facilitate construction of the spindle, an angle of about 30° being entirely satisfactory from both standpoints.

To operate my novel spindle, the yarn is first threaded from the spool 26 through the passages 19 and 50 and then upward to the usual stationary guide and winding mechanism above the spindle, and the spindle, is then started. As explained above, as soon as the balloon of the yarn begins to provide a tangential component of yarn tension, the yarn slides downwardly along the working yarn guiding edge 48 to the flange surface 44, the outward slant of said surface being sufficient to prevent further downward movement of the yarn. Thus, when the spindle is revolving, the yarn S is fed from the storage wheel opening at the lower side of the storage wheel surface, and from there is moved upwardly by the upward component of yarn tension provided by the winding mechanism so that at no time can a plurality of turns of yarn on the storage wheel surface be in overlapping relationship.

Although the slanted upper surface 44 of flange 42 effectively maintains the yarn on storage wheel cylindrical surface 40 as long as the yarn is passing upwardly to the winding mechanism, when the yarn is broken at a point between the axial spindle yarn passage and the winding mechanism, the loss of an upward component of yarn tension allows the weight of the yarn itself to move the broken yarn downwardly over the slanted flange surface 44 and below the storage wheel. The yarn will then be wound up on the reduced diameter in groove 46 by the rotating spindle and will be prevented from continuously being fed outwardly from the storage wheel opening.

Thus, in my novel 2 for 1 spindle storage wheel structure, it will be seen that I have provided a surprisingly simple and effective means which simultaneously solves the aforementioned problems of overlapping turns of yarn and of continued feeding when the yarn breaks.

While I have herein disclosed and described a preferred embodiment of the invention, it will be understood that the same is susceptible of various modifications and changes within the spirit of my invention and the scope of the appended claims.

I claim:

1. In a two for one twister having a rotatable spindle with an axial yarn passage for drawing off the yarn therethrough, a yarn storage wheel with an outer substantially cylindrical surface concentric to and extending lengthwise of said spindle mounted on said spindle

for rotation therewith, said wheel having an outer opening in said surface having a yarn guiding edge slanted with its upper end leading its lower end in the direction of rotation of said spindle, and said spindle having a yarn passage leading from said axial yarn passage to said outer opening, said yarn guiding edge being effective upon rotation in a direction with its upper end leading to provide a downward sliding component upon and guide in a downward direction yarn passing from said outer opening to prevent overlapping of a plurality of turns of yarn wrapped about said storage wheel outer surface.

2. In a two for one twister as claimed in claim 1, wherein the angle of slant of said yarn guiding edge is at least 5° from the axis of said spindle.

3. In a two for one twister having a rotatable spindle with an axial yarn passage for drawing off the yarn therethrough, a yarn storage wheel with an outer substantially cylindrical surface concentric to and extending lengthwise of said spindle mounted on said spindle for rotation therewith, said wheel having a lower flange extending outwardly from said cylindrical surface, an outer opening in said surface having a yarn guiding edge slanted with its upper end leading its lower end in the direction of rotation of said spindle, and said spindle having a yarn passage leading from said axial yarn passage to said outer opening, said yarn guiding edge being effective upon rotation in a direction with its upper end leading to provide a downward sliding component upon and guide in a downward direction toward said flange yarn passing from said outer opening to prevent overlapping of a plurality of turns of yarn wrapped about said storage wheel outer surface.

4. In a two for one twister having a rotatable spindle with an axial yarn passage for drawing off the yarn therethrough, a yarn storage wheel with an outer substantially cylindrical surface concentric to and extending lengthwise of said spindle mounted on said spindle for rotation therewith, said wheel having a lower flange extending outwardly from said cylindrical surface, an outer opening in said surface extending through the lower edge of said wheel and having a yarn guiding edge slanted with its upper end leading its lower end in the direction of rotation of said spindle, and said spindle having an open yarn passage leading from said axial yarn passage to said outer opening, said yarn guiding edge being effective upon rotation in a direction with its upper end leading to provide a downward sliding component upon and guide in a downward direction toward said flange yarn passing from said outer opening to prevent overlapping of a plu-

rality of turns of yarn wrapped about said storage wheel outer surface.

5. In a two for one twister having a rotatable spindle with an axial yarn passage for drawing off the yarn therethrough, a yarn storage wheel with an outer substantially cylindrical surface concentric to and extending lengthwise of said spindle mounted on said spindle for rotation therewith, said wheel having a lower flange extending outwardly from said cylindrical surface, the upper surface of said flange being slanted outwardly and downwardly, an outer opening in said surface extending through the lower edge of said wheel and having a yarn guiding edge slanted with its upper end leading its lower end in the direction of rotation of said spindle, and said spindle having an open yarn passage leading from said axial yarn passage to said outer opening, said yarn guiding edge being effective upon rotation in a direction with its upper end leading to provide a downward sliding component upon and guide in a downward direction toward said flange yarn passing from said outer opening to prevent overlapping of a plurality of turns of yarn wrapped about said storage wheel outer surface.

6. In a two for one twister as claimed in claim 5 wherein said flange surface is slanted downwardly at an angle of between 20° and 60° from the axis of said spindle.

7. In a two for one twister as claimed in claim 5 further having an annular groove around said spindle immediately below said storage wheel for holding the yarn end upon breakage of the yarn and the downward passage of said broken yarn over said slanted flange.

8. In a two for one twister as claimed in claim 1 wherein said yarn storage wheel has a lower flange extending outwardly from said cylindrical surface, the upper surface of said flange being slanted outwardly and downwardly from said cylindrical surface, and an outer opening in said surface extending through the lower edge of said wheel, said spindle having an open yarn passage leading from said axial yarn passage to said outer opening, and said spindle having an annular groove immediately below said storage wheel for holding the yarn upon breakage of the yarn and the downward passage of said broken yarn over said slanted flange.
